ROTATABLE RACK FOR STEREO TAPES

William Levy, Glen, N.H., assignor to Standard International Corporation, Andover, Mass., a corporation of Ohio

Filed Mar. 7, 1969, Ser. No. 16,117

Term of patent 14 years

Int. Cl. D6—01

U.S. Cl. D33—3

FIG. 1

FIG. 4

FIG. 1 is a front elevational view of a rotatable rack for stereo tapes or similar article showing my design, FIG. 2 is a top plan view,

FIG. 3 is a bottom plan view; and

FIG. 4 is a perspective view thereof.

The two sides not shown in FIG. 4 are mirror images of the sides shown.

I claim:

The ornamental design for a rotatable rack for stereo tapes, substantially as shown.
